UNITED STATES PATENT OFFICE

FRANKLIN R. WHITE, OF WATERBURY, WALTER T. ABEL, OF WATERVILLE, AND LEONARD R. CARLEY, OF WATERTOWN, CONNECTICUT, ASSIGNORS TO THE PATENT BUTTON COMPANY, OF WATERBURY, CONNECTICUT, A CORPORATION OF CONNECTICUT

STAPLE BUTTON

Application filed July 16, 1929. Serial No. 378,678.

Our invention relates to new and useful improvements in buttons, and more particularly to that type of button known as a "staple button".

5 The invention broadly contemplates a hollow shell in which there is placed an anvil or die, the shell being provided with an imperforate hub. The two pronged staple is driven up through the bottom of the hub, and the 10 prongs contacting with the die are guided or turned downwardly, so that they will, in their deformed state, lie adjacent to each other and jam down against the metal at the bottom of the hub to thus tightly hold the 15 button to the cloth.

One of the objects of the present invention is to provide a very simple button similar in its broadest aspect to the button shown 20 in Patent, No. 1,463,236, granted to Franklin R. White on July 31, 1923.

In that instance, the die was provided with two concave surfaces to throw the prongs of the staples outwardly, whereas in the present instance the die or anvil has only one concave surface and is so formed as to throw the deformed prongs toward each other, lie adjacent and contact with the central chamber in the bottom of the hub.

30 Still another object of the invention is to provide a staple button wherein the imperforate base is provided with a centrally depressed ring, so that the prongs of the staple will be guided in their initial piercing properly against the die or anvil and lock in the metal centrally of the depressed ring.

With these and other objects in view, the invention consists in certain new and novel 40 arrangements and combination of parts as will be hereinafter more fully described and pointed out in the claims.

Referring now to the drawings showing an embodiment of our invention,

45 Fig. 1 shows a sectional view of the button,

a fragmentary piece of cloth and a staple about to be inserted;

Fig. 2 shows a fragmentary piece of cloth with one button in side elevation and the other button in its attached position in section;

Fig. 3 is a sectional view of the cover, anvil and shell of the button separated;

Fig. 4 is a top plan view of the button, a part of the cover being broken away for the sake of clearness;

Fig. 5 is a top plan view of the shell;

Fig. 6 is a perspective of the staple; and

Fig. 7 is a perspective of the die or anvil.

At the outset, it might be stated that this is also what is known as a "closed top button," so that the cover or shell may have any desired insignia pressed therein. It might also be mentioned that the several views show the button in a greatly enlarged state which was done simply for the purpose of clearness of illustration and to show the manner in which the staple is jammed into the bottom of the hub of the button.

Referring now more particularly to the several views, there may be seen the button shell which comprises the body 1 which is a relatively flat portion and is provided with the upwardly and outwardly extending rim 2. Centrally of the shell and integrally formed therewith is the hub 3, the sides of which may taper slightly toward its lower extremity, while across the bottom of the hub may be seen the imperforate base 4, which is provided with the small depressed ring 5,

thus forming the slight depression or chamber 6 within the hub, as may be seen in the several views.

Located within the hub is the anvil or die 7 having the plate 8 which is of sufficient diameter to rest on the body portion of the button head, while formed integral with this plate 8 is the head 9, which also slightly tapers to fit loosely within the hub of the shell.

The bottom surface of this head 9 is provided with the concave chamber 10, which extends directly above the depressed portion 6 in the bottom of the hub and over the depressed ring portion 5 formed in the bottom surface or base of the hub.

After the anvil is placed in position, a cover plate 11 is secured about the peripheral rim 2 to hold the anvil in place and complete the button head. It might be mentioned here that the anvil serves a double function, in that when the button is attached, that is, when the staple is driven up through the goods and against the anvil, there must be a plunger or block against the cover or top surface of the button, and this anvil within the shell forms a support for the cover and prevents any marring of any insignia on the cap of the button. We have not shown any insignia on the cap, but it is so well understood in the art that these buttons may have the brand or name thereon that it was not thought necessary to illustrate the insignia.

Glancing at Fig. 6 for the moment, there will be seen a staple 12 provided with the prongs 13 and 14, these staples being generally cut from a metal blank and then provided with the small cap 15 so as to provide a neat appearance and to clinch or clamp the goods on the inner surface.

Looking at Fig. 2 for the moment and to the sectional button where it is shown as attached, there may be seen the piece of cloth 16, while the prongs 13 and 14 of the staple have been driven through the cloth and have pierced the base 4 of the bottom of the hub, the prong, of course, first contacting with the metal walls of the ring portion 5. The near prong 13 in Fig. 2 is shown as having struck the die and as having been guided from the left toward the right, as may be clearly seen in this view. In the same manner, the prong 14, when striking the die, has been guided toward the left, that is, the point thereof, so that it will assume the position shown in Fig. 4. In other words, the two staple prongs when in their finally deformed position lie adjacent one another and extend in the opposite directions and also over or in the small concave chamber 6 in the base of the hub and, in fact, may be jammed down within this chamber.

It will thus be seen that after the staple is once driven through the cloth up into the button head and guided downwardly, the prongs will tightly hold the button to the cloth.

By setting the head of the die nearly adjacent with the inner bottom surface of the hub, the prongs of the staples will be jammed downwardly into the hub and in their finally deformed state may be even more mutilated than that shown in Fig. 2. In other words, the metal of the prongs is all jammed down

into the bottom of the hub to thus more tightly hold the button in position.

It might also be mentioned that the metal about the pierced holes will be curved back and the prong of the staple will also be jammed down against these jagged edges to more tightly hold the button in position.

By providing a staple button of this character, a closed top button may be used and the cover may have insignia thereon which will not be in any way mutilated when the button is attached in the standard button attaching machines, because the anvil not only deflects the staple prongs correctly but supports the cover plate when the plunger above the button contacts with the cover while the tack is being driven up within the imperforate hub.

Having thus described our invention, what we claim as new and desire to secure by Letters Patent is:

1. A staple button comprising a shell, said shell having a body portion, a hollow hub and an imperforate base, an anvil in said shell and a cover over said shell, said anvil provided with a head projecting down within the hollow hub and in close proximity to the base, the lower surface of the head being provided with a concave chamber and the base of the hub having a depression opposite the said concave chamber and a ring portion formed therein, the ring portion adapted to guide the prongs of a staple against said die and downwardly to nest in the depression in the base.

2. A staple button comprising a shell, the shell having a body portion and an upwardly extending rim, a cover over said rim, an anvil in said button and resting on the body portion thereof and said anvil provided with a head extending downwardly in said hub, said hub having an imperforate base and a depressed ring portion formed in said base to provide a central chamber in said base, the said ring portion adapted to guide the prong of a staple against said die and turn said staple toward each other and nest in the depression formed in said base.

3. A closed top button comprising a shell having a body portion, an upwardly extending peripheral rim, an integral hub and an imperforate base for said hub, an anvil within said shell and a cover resting against the upper surface of said anvil and said cover secured to said peripheral rim, said anvil having a head fitting downwardly in said hub, the base having an impressed ring portion and a consequential depressed chamber, a two pronged staple adapted to be driven through the ring portion of said base, the prongs of the staple deflecting against said anvil and jammed toward each other and nesting in the central chamber of the base.

4. A closed top button comprising a shell, a cover formed in said shell, the said shell having a hub and an imperforate base, an

anvil in said shell, said anvil having a concave chamber above said base, said base having a central chamber of less diameter than the diameter of the chamber in the hub, and the said chambers being directly opposite each other and forming substantially one chamber and the portion of said chamber in said base adapted to receive the end portions of the mutilated prongs of a staple to thereby hold the button to the article to which it is to be attached.

In testimony whereof we affix our signatures.
